(57) **CLAIM**

The ornamental design for a recycler, as shown and described.

DESCRIPTION

FIG. 1 is a right side perspective view of a recycler showing my new design;

FIG. 2 is a left side perspective view thereof;

FIG. 3 is a left side elevational view thereof;

FIG. 4 is a right side elevational view thereof;

FIG. 5 is a front elevational view thereof;

FIG. 6 is a rear elevational view thereof; and,

FIG. 7 is a top plan view thereof.

The broken dash lines comprise claim boundaries. Neither the portions inside the broken dash lines nor the broken dash lines themselves form any part of the claimed invention.
